UNITED STATES PATENT OFFICE.

EDWARD J. DOBERSTEIN, OF BLUE ISLAND, ILLINOIS, ASSIGNOR TO GOODMAN MANUFACTURING COMPANY, OF CHICAGO, ILLINOIS, A CORPORATION OF ILLINOIS.

MINING-MACHINE SKID.

Application filed July 13, 1923. Serial No. 651,290.

This invention relates to transportation devices for mining machines and has for its principal object to provide auxiliary draft means for transporting an undercutting machine from place to place along the mine floor for greater distances or at a higher rate of speed than is ordinarily practicable with machines of this character.

More specifically, my invention is adapted particularly for use in connection with a continuous cutting or shortwall type of mining machine used primarily for undercutting coal in the room and pillar system of mining, and consists in providing a supporting skid carrying an auxiliary winding drum and draft cable thereon, adapted to be detachably connected with the power devices on the cutting mechanism when the latter is mounted on said skid, whereby the cutting mechanism may be transported from cutting place to cutting place, said cutting mechanism and skid requiring a minimum overhead clearance, as is desirable under many conditions of mining. This operation of transporting a cutting mechanism intermediate cutting places along the ground is commonly referred to as "flitting" in some localities. Furthermore, the cutting mechanism and auxiliary skid may be mounted and carried bodily upon a wheeled mining machine truck, the latter also having power connections with the mining machine motor, whereby the entire apparatus may be transported along mine tracks in the usual manner, where tracks are available.

Other and further objects and advantages of my invention will appear from time to time as the following description proceeds:

The invention may be best understood by reference to the accompanying drawings illustrating one form in which my invention may be embodied:

In these drawings:

Figure 1 is a plan view of a cutting apparatus including a cutting mechanism of the shortwall type, and an auxiliary transporting device constructed in accordance with my invention, both being mounted upon a mining machine truck.

Figure 2 is a side view of the apparatus shown in Figure 1, with parts cut away to show details of gearing of the cutting apparatus.

Figure 3 is a plan view of the transporting unit forming an important part of my present invention.

Figure 4 is a longitudinal section taken on line 4—4 of Figure 3.

Figure 5 is a transverse section taken on line 5—5 of Figure 3.

Figure 6 is a transverse section taken on line 6—6 of Figure 4.

Figure 7 is a transverse section taken on line 7—7 of Figure 4.

Figure 8 is an enlarged detail of cable retaining sheaves shown in Figure 7.

Figure 9 is a diagram illustrating a typical method in which my improved apparatus may be utilized in the room and pillar system of mining.

For the purpose of illustration, my invention is shown as applied to a cutting mechanism 10 of the shortwall type, and a wheeled truck 11, of the type usually employed for supporting and carrying such cutting mechanisms, excepting when withdrawn therefrom for sliding movement along the mine floor during actual cutting operations. Cutting mechanisms and machine trucks of the type mentioned may vary widely in construction, but usually have certain common characteristics. For instance, the cutting mechanism 10 is provided with a shoe 12 upon which the cutting mechanism is mounted for sliding movement on the mine bottom during the cutting operations. The cutting mechanism is further provided with a cutting element, as for example, a cutter bar 13 of the ordinary type having an endless cutter chain (not shown), movable thereabout. The machine is controlled and fed to the work by means of flexible draft ropes 14 and 15, wound respectively on drums 16 and 17. The cutting and feeding mechanisms are driven by a motor 18, one or both of the drums 16 and 17 having driving engagement with said motor, as desired. Details of the power gearing on the cutting mechanism need not be described in detail, excepting to point out by way of illustration the mechanism whereby the motor 18 may be detachably connected for operating the auxiliary draft device carried by the supporting skid and also to form driving connection with the truck. The power connections carried by the body of the cutting mechanism 10 may

include the longitudinally disposed shaft 19 having a socket 20 at the rear end of the machine frame, arranged for detachable engagement by a tongue 21^a on the end of a shaft 21. The shaft 19 is connected to the motor shaft 22 by suitable gearing, as for instance, gear pinions 23 and 24.

The construction of the supporting skid indicated generally by the numeral 25 will now be described. Said skid is designed to receive and support the cutting mechanism 10 and to this end comprises an elongated body portion or frame 26 preferably provided with lateral flanges or guides 27, 27, extending upwardly so as to receive the bottom plate 12 of the cutting mechanism therebetween. The front end of the frame 26 is open, the flanges 27, 27 being flared outwardly, so that the cutting mechanism 10 may be readily loaded thereon. An apron 28 is connected to the front end of said frame in position to be dropped into engagement with the ground at its forward edge, as shown in dotted lines in Figure 4, to facilitate the loading of the cutting mechanism thereon. In the form shown this apron 28 has hinged connection with the frame 26 by means of a pair of downwardly extending flanges 29, 29, extending through slots 30, 30, and having stop members 31, 31 securing said flanges in place, but permitting the apron limited vertical pivotal movement as desired.

It will be understood that when in operation the supporting skid 25 together with the cutting mechanism 10 are adapted to be unloaded bodily from the mining machine truck 11, to be slid universally over the mine floor, and particularly for "flitting" from one cutting place to the next. In the form shown, the skid is provided with a pair of runners 35, 35, extending longitudinally along opposite sides of and underneath the frame 26. These runners are rigid with respect to the frame 26, being connected thereto by any suitable means, such as welding or riveting.

The auxiliary draft device is mounted at the rear end of the skid and comprises a winding drum 40. In the form shown this drum is carried on a horizontally disposed shaft 41, extending transversely of the skid and suitably supported on brackets 42, 42 at the sides of the frame, and a bracket 43 disposed centrally of the frame. This winding drum may be of relatively large proportions, so as to carry a draft cable 45 much longer than either of the draft cables 14 or 15, heretofore described as being part of the feeding mechanism of the cutting apparatus 10. The drum is adapted to be driven by means of the motor 18 on the cutting mechanism when the latter is loaded upon the supporting skid 25 as shown in Figures 1 and 2. In this position, as has already

been indicated in connection with the foregoing description of the cutting mechanism, the shaft 21 is connected with a socket 20 on the rear end of the power driven shaft 19 operatively connected with the motor 18. 70 The shaft 21 has a squared portion 48 intermediate its ends, fitting within a worm gear 49. Said worm gear is journalled in the central bracket 43 and is meshed with a worm wheel 50, also journalled in bracket 43, as best shown in Figure 5. The worm wheel 50 is keyed on a hollow shaft 51 loosely mounted for rotation on the shaft 41, and having a clutch member 52 at one end thereof adapted for detachable engagement with a co-acting clutch member 53. In the form shown the co-acting clutch members 52 and 53 are of the cone type, but it will be understood that any other suitable clutch device may be provided, as desired. The clutch member 53 is feathered on the shaft 41 so as to provide a driving connection for drum 40, keyed on the opposite end of said shaft. 80

From the above description, it will now be clear that the cutting mechanism 10 may be loaded upon the supporting skid 25 in position to form an operative connection between the cutting mechanism motor 18 and the winding drum 40. The cutting mechanism is preferably loaded upon the skid when the latter is resting upon the ground, as indicated in Figure 4. In this position, the outer end of the apron 28 at the front end of the skid is dropped into engagement with the ground, as shown in dotted lines. 90 A pair of longitudinal extending support plates 55, 55, are provided along opposite sides of and above the frame 26, along which plates the bed frame or shoe 12 of the cutting mechanism is adapted to slide. A 100 pair of stops 56, 56 are secured to the frame 26 to limit the rearward movement of the cutting mechanism 10 respective to the skid at the proper position to form an operative connection between the cutting mechanism and the drum 40, carried by the skid, as 110 shown in Figures 1 and 2.

The rear end 60 of the shaft 21 extends rearwardly beyond the support 43 of the skid in position to be detachably engaged by 115 a driving shaft 61 carried by the mining machine truck 11. The shaft 61 is operatively connected to the supporting wheels 62, 62 of the truck by any suitable mechanism, as for instance, a worm gear 63 and 120 worm 64, the latter mounted on a transverse shaft 65 having sprocket 66 thereon. A drive-chain 67 is trained over sprocket 66 and a sprocket 68 secured in the usual manner to the rear truck wheel 62. 125

In connection with the improved supporting skid and auxiliary draft mechanism forming a part of the present invention, I provide means whereby cable 45 carried thereby may be extended either forwardly 130

or rearwardly of the cutting mechanism and skid when the latter are cooperatively engaged for movement along the mine floor. This means comprises suitable guides 5 mounted on the skid about which the draft cable 45 may be trained. In the form shown said draft cable may be extended forwardly of the apron by means of a sheave 70 carried on the floor of the skid and immediately 10 in front of the drum 45. Said sheave is preferably mounted upon an inclined axis, as shown in Figure 4, in position to permit the rope 45 to be passed thereabout and thence laterally about a vertically disposed sheave 71, disposed centrally of the frame 26. The central portion of the frame 26 between plates 55, 55, is preferably open, as indicated at 73, so as to permit the rope 45 to pass freely underneath the bottom 15 shoe 12 of the cutting mechanism when it is mounted on the skid. A pair of oppositely disposed sheaves 72, 72, are mounted on a bracket 77 extending across the opening 73 at the forward end of the skid, these latter 20 sheaves being arranged below the top surface of and between the plates 55, 55, upon which the bottom plate 12 of the cutting mechanism rests. The free end of the rope may thus pass beneath the apron 28 25 where it may be anchored in advance of the skid and cutting mechanism to pull the entire mechanism bodily in a direction longitudinally of the cutting mechanism and cutter bar.

30 In order to assure proper alignment of the draft rope 45 when extended underneath the cutting mechanism, as described, the oppositely disposed sheaves 72, 72, at the forward end of the pan are arranged with their peripheries sufficiently close to each other to retain said draft rope therebetween. The 35 sheaves are normally retained in place by suitable means, such as retaining pins 75, 75, extending through the respective studs 76, 76, upon which said sheaves are mounted and journaled in the bracket 77. It will be seen that when the cutting mechanism is unloaded from the skid, the pins 75, 75 may be removed so as to permit the sheaves 72, 72 40 to be withdrawn and thus release the cable 45.

45 Suitable guide devices are also provided to permit the cable 45 to be extended toward the rear of the apparatus, as for instance by a sheave 80 mounted on an inclined axis behind the drum, and a co-acting sheave 81 disposed centrally of the skid and about which the cable 45 may be trained, as indicated in dotted lines in Figure 3.

50 The use and advantages of the device above described are as follows:
55 When the supporting skid 25 is on the mine floor as shown in Figure 4, the cutting mechanism may be loaded thereon by means 60 of the draft cables 14 or 15 carried on the

machine and operated in the usual manner under power of the machine motor 18. The apron 28 of the skid is dropped into position to receive the rear end of the supporting shoe 12 and the mechanism is drawn rearwardly onto the skid as for instance, by anchoring the free end of one of said draft cables to the support 43 at the rear end of the skid. The loading operation is similar to the well known operation of loading a cutting mechanism of this character upon the mining machine truck. The cutting mechanism is drawn rearwardly until the rear end of the shoe 12 engages the stop 56 on the skid. In this position the motor is 70 stopped, and the tongue 21 of driving shaft 21 is fitted in the socket 20, carried by the cutting mechanism. When loaded on the supporting skid in the position shown in Figure 1, the apron 28 will be raised into horizontal position, owing to the pressure of the forward portion of the shoe 12, which maintains said apron in a horizontal position in alignment with the supporting strips 55, 55. The cutting mechanism may be then 80 locked from endwise movement respective to the skid by inserting a locking pin 85 through the side flange 27 of the skid and the underframe 86 of the cutting mechanism. The cutting mechanism and skid are then 85 in position to be moved or "flitted" along the mine floor, and for this purpose the draft rope 45 may be trained either forwardly over sheaves 70, 71 and 72 or rearwardly 90 over sheaves 80 and 81. The cutting mechanism may be unloaded from the skid by the reverse of the loading operation described.

95 The drive gearing for the drum 40 is such as to wind the draft rope 45 at a considerably higher speed than that usually provided for by feeding drums 16 or 17 on the cutting mechanism during the usual cutting operation and movement of the machine adjacent the working face. This greater flitting speed has been found highly desirable 100 under most conditions. In the present instance, the higher flitting speed is afforded without adding any mechanism to the body of the cutting mechanism, such as might materially affect its usefulness by increasing 105 its dimensions or weight. The present arrangement provides this additional gearing in the form of a detachable unit, which is brought into operation only when required, for "flitting", after the cutting mechanism 110 has been withdrawn from its cutting operations at the face. It will be further noted that it is possible to provide a winding drum having a much larger capacity, for

115 flitting over much greater distances than would be practicable if applied directly to the cutting mechanism, it being understood that in machines of the shortwall or continuous cutter type it is desirable to limit the size of the winding drum as near as pos- 120 125 130

sible to the actual requirements for cutting across a relatively short working face, say 30 to 50 feet. On the other hand, it is usually necessary to "flit" the machine much greater distances, as for instance, the entire length of a mine room, ranging from 100 to 300 or more feet in length, as illustrated in Figure 9. In this diagram the mine tracks 90, 90 are not extended into the room 91, so that the mining machine truck 11 can be moved only to the entrance 92. By means of the supporting skid 25 herein disclosed, the machine 10 may be transported on the skid 25 between the point of unloading at the room entrance 92 and the working face 93, where it is in turn unloaded from the skid to perform its cutting operations in the usual manner.

It will be further understood that the supporting skid 25 may be used for flitting between cutting places without a wheeled truck, for under some conditions it has been found entirely impracticable to use a truck of any description, especially in some mines where no tracks are available, and in other conditions where the overhead clearance is not sufficient to permit the use of a wheeled truck. In extremes of the latter conditions, it will be obvious that the overall height of the entire cutting mechanism and skid truck may be reduced to a minimum by reducing the height of the runners 35, 35 on the bottom of the skid.

Although I have shown and described one form in which my invention may be embodied, it will be understood that the construction and arrangement of the parts may be varied without departing from the spirit and scope of the invention. I do not therefore, wish to be understood as limiting myself to the specific construction illustrated herein, excepting as specifically limited in the appended claims.

I claim as my invention:

1. In combination with a draft operated cutting element, adapted for movement along the mine floor, a supporting skid, and auxiliary winding devices on said skid located within prolongations of the longitudinal boundaries of said cutting element.

2. In combination with a cutting mechanism having power devices thereon, an auxiliary winding device bodily detachable from and connectable with said power devices at one end of said cutting mechanism within prolongations of the longitudinal boundaries of the latter.

3. In combination with a cutting mechanism, having flexible draft feeding means and an actuator for operating the same, an auxiliary winding device bodily detachable from and connectable with said cutting mechanism and having geared connection with said actuator independent of said feeding means to drive said auxiliary draft means

at a greater rate of speed than said feeding devices on the cutting mechanism.

4. In combination with a cutting mechanism having flexible draft feeding means including a winding drum, an auxiliary winding device including a winding drum of greater capacity than the feeding drum on the cutting mechanism, and means detachably connecting said auxiliary draft device bodily with said cutting mechanism within the prolongations of the longitudinal boundaries of the latter.

5. The combination with a cutting mechanism having flexible feeding devices for moving the same universally over the mine floor during the cutting operation, and provided with an actuator, of a supporting skid upon which said cutting mechanism may be carried, having auxiliary flexible draft means thereon, detachably connectable with said actuator.

6. The combination with a cutting mechanism having flexible feeding devices for moving the same universally over the mine floor during the cutting operation, and provided with an actuator, of a supporting skid upon which said cutting mechanism may be carried, having auxiliary flexible draft means thereon detachably connectable with said actuator, and guide devices on said skid about which the auxiliary flexible draft means may be trained longitudinally of the skid in either direction.

7. In combination with a cutting mechanism having an actuator thereon, a wheeled truck for said cutting mechanism, a skid upon which the cutting mechanism may be mounted in interposed relation between said mechanism and said truck, a power device on said skid including an auxiliary flexible draft device, detachable power connections between said actuator and said power devices, and other detachable power connections between said power device and the truck wheels.

8. In combination with a cutting mechanism having an actuator thereon, a wheeled truck for said cutting mechanism, a skid upon which the cutting mechanism may be mounted in interposed relation between said mechanism and said truck, a power device on said skid including an auxiliary flexible draft device, detachable power connections between said actuator and said power devices, other detachable power connections between said power device and the truck wheels, and a clutch interposed between said power device on said skid and the auxiliary draft means, whereby the latter may be disconnected and the mining machine truck be driven by the actuator on the cutting mechanism.

9. In combination with a cutting mechanism having flexible draft feeding means, including a winding drum, a skid upon which

said cutting mechanism may be mounted, an actuator for said winding drum, an auxiliary draft device on said skid including a winding drum of greater capacity than the feeding drum on the cutting mechanism, means detachably connecting said auxiliary draft device and said cutting mechanism,

and detachable speed reducing gearing connections between said auxiliary winding drum and said actuator.

10

Signed at Chicago, in the county of Cook and State of Illinois, this 9th day of July, 1923.

EDWARD J. DOBERSTEIN.
